HEAT EXCHANGE UNIT

Clarence A. Leidig, Buffalo, N. Y., assignor of forty-five per cent to Silas C. Wead, North Tonawanda, N. Y.

Application December 4, 1936, Serial No. 114,218

7 Claims. (Cl. 257—247)

This invention relates to a new and improved heat exchange unit and particularly to a device for elevating the temperatures of liquids by means of a current of hot gas, but which is susceptible of other uses, as for instance, by placing the unit in a surrounding medium of low temperature and passing through the unit a liquid which is to be cooled.

It is an object of the present invention to provide a device which may be arranged within small compass, as for instance in a conduit for hot gases, and one which will offer a minimum of resistance to the normal flow of gas in the conduit and at the same time will take a comparatively large proportion of the heat from the gas and transfer it to the fluid passing through the heat exchange unit.

In one application of my invention the heat transfer unit which forms the subject matter of the present invention is disposed in the exhaust conduit of an internal combustion engine.

The internal combustion engine may be the propelling means for an aeroplane and the heat taken from the exhaust gases by use of the present invention may be used for heating the cockpit.

In installations of this class thermal efficiency, minimum resistance to the free passage of the exhaust gas in the conduit, and compactness and light weight are extremely important considerations. My invention affords a device which meets these requirements and which is of simple construction. Of course, the particular desirability of my device in the instance suggested does not render it less fit for use in other cases where an efficient, compact heat exchange unit is required.

In the accompanying drawing, I have illustrated the embodiment of my invention which I at present prefer but it is to be understood that the form there disclosed is merely exemplary and that many modifications might be made without departing from the spirit or scope of the invention as defined in the appended claims.

In the drawing

Fig. 1 illustrates one form of my present invention in side elevation and disposed in a hot gas conduit. Parts of the heat transfer unit have been broken away to better illustrate the interior construction;

Fig. 2 is a cross sectional view taken on the line 2—2 of Fig. 1;

Fig. 3 is a partial cross sectional view taken on line 3—3 of Fig. 1;

Fig. 4 is a view similar to Fig. 2 showing a modified form of my invention.

In Fig. 1 of the drawing 10 designates the confining chamber for the medium which is to give off or take on heat to effect a change in temperature of the fluid passing through the unit. In the present instance this confining chamber is the exhaust conduit of the internal combustion engine of an aeroplane and one form of my present invention is shown disposed therein. The form illustrated in Figs. 1, 2 and 3 includes a series of flattened tubes 11, 12 and 13. While in the form illustrated these tubes are three in number it will be understood that any suitable number of similar tubes may be added to the series.

Disposed within the tubes 11, 12 and 13 are similar but smaller flattened tubes 14, 15 and 16 which are supported centrally of the tubes 11, 12 and 13, respectively, by spacing blocks 16 disposed adjacent the ends of the tubes and welded thereto. Each pair of inner and outer tube members defines an elongated fluid passage or chamber of annular cross section.

The several tubes 11, 12 and 13 are joined to each other and maintained in spaced parallel relation with their flat side portions facing each other by blocks 17 and 18 which are disposed between each pair of tubes at their opposite ends and welded thereto.

End plates 21 and 22 are provided whose circumferential configurations coincide with the outline of the ends of the assembled group of tubes 11, 12 and 13. Openings 23 are provided in the end plates 21 and 22 and these openings are of the same contour as the interior of each of the smaller flattened tubes 14, 15 and 16.

A suitable number of tie bolts 24 are preferably provided, each of which extends through both end plates 21 and 22 at such points that the intermediate portion of each tie bolt passes through the space between the outer and inner flat tubes at their end portions at which points the annular space is of greater width than at the flat side portions.

The lowermost tube 13 of the series is provided adjacent one of its ends with an inlet pipe 26 and from the upper surface of the tube 11 there extends an outlet pipe 27 which is disposed at the opposite end of the device from the pipe 26 when, as in the present instance, the number of tubes is odd, but is disposed at the same end of the device as pipe 26 when an even number of tubes are used.

When the tubes and end plates are assembled a plurality of closed annular compartments or passages are provided between each pair of outer

and inner flattened tube members. These compartments are interconnected in a manner which will now be described. The bottom portion of the tubular member 11 is notched at the end opposite the outlet pipe 27 and the block 17 lying immediately between the tube 11 at this point and the top of the tube 12 is similarly notched to form the passageway 28 which appears in Fig. 3. The tubes 12 and 13 are in like manner provided with a similar passageway 29 extending between them and lying at the opposite end of the device from the passage 28.

When the device is installed for use the pipes 26 and 27 are connected in a normally closed fluid circuit (not shown) and the heat of the exhaust gases emitted by the internal combustion engine passes through the conduit 10 and surrounds the outer surfaces of all of the tubes 11, 12 and 13 and the inner surfaces of the tubes 14, 15 and 16. This construction I have found to give highly efficient results, having in mind the most satisfactory balance or proportion between area of radiation, freedom of flow of the hot gas and the fluid to be heated, and at the same time giving consideration to the requirements of sturdiness and economy of manufacture. In this way heat is transferred from the exhaust gas of the engine to the water or other fluid which occupies the annular spaces between the tubes 11, 12 and 13 of the tubes 14, 15 and 16 respectively causing the heated fluid to rise and emerge through the pipe 27 and additional supplies of cool fluid to enter the heat exchanger through the pipe 26.

It will be seen that owing to the disposition of the interconnecting passages 28 and 29 at alternate ends of the device the fluid is caused to take a circuitous path which completely traverses the annular spaces between each of the tubes from the pipe 26 to the outlet 27. The fluid passes from left to right, as seen in Fig. 1, through the space between the tubes 13 and 16, through the passage 29 and then from right to left in the space between the tubes 12 and 15, then through the passage 28 and from left to right through the space between the tubes 11 and 14 and out of the outlet pipe 27.

A modification of the form of invention illustrated in Figs. 1, 2 and 3 is shown in Fig. 4 wherein the spacing blocks 17 and 18 are omitted and the outer tubes 11, 12 and 13 are secured directly to each other as by welding or the like. The device illustrated in Fig. 4 is in all other respects substantially the same in construction and operation as the device illustrated in Figs. 1, 2 and 3. In the device of Fig. 4 a part of the radiating surface is sacrificed to secure greater compactness of construction.

What is claimed is:

1. A heat exchange unit comprising a series 60 of tubular members arranged in parallel relationship, a second series of tubular members of smaller cross-sectional area than said first series, one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several members for closing off said annular spaces and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, an inlet port for communicating with the annular chamber at one end of said series of tubular members and an outlet port communicating with the annular chamber at the opposite end of said series of tubular members, and tie rods extending between said end closure members and engaging therewith to retain said closure plates in a fluid-tight manner against the ends of said tubular members in assembled relation.
2. A heat exchange unit comprising a series of tubular members arranged in parallel relationship, a second series of tubular members of smaller cross-sectional area than said first series, one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several tubular members for closing off said annular spaces and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, an inlet port for communicating with the annular chamber at one end of said series of tubular members and an outlet port communicating with the annular chamber at the opposite end of said series of tubular members, and tie rods extending between said end closure members and engaging therewith to retain said closure plates in a fluid-tight manner against the ends of said tubular members in assembled relation, the intermediate portions of said tie rods being disposed within said annular fluid chambers.
3. A heat exchange unit comprising a series of tubular members arranged in parallel relationship, a second series of tubular members of smaller cross-sectional area than said first series, one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several tubular members for closing off said annular spaces and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, an inlet port for communicating with the annular chamber at one end of said series of tubular members and an outlet port communicating with the annular chamber at the opposite end of said series of tubular members, and tie rods extending between said end closure members and engaging therewith to retain said closure plates in a fluid-tight manner against the ends of said tubular members in assembled relation, the intermediate portions of said tie rods being disposed within said annular fluid chambers.
4. A heat exchange unit comprising a series of

series of tubular members are utilized in radiating heat, passages for establishing communication between adjacent annular chambers, said passages being disposed alternately at opposite ends of said tubular members, and an inlet port 5 for communicating with the annular chamber at one end of said series of tubular members and an outlet port communicating with the annular chamber at the opposite end of said series of tubular members.

2. A heat exchange unit comprising a series of tubular members arranged in parallel relationship, a second series of tubular members of smaller cross-sectional area than said first series, one each of said second series of tubular members 15 being arranged centrally within each of said first series of tubular members to provide annular fluid chambers therebetween, said inner and outer tubular members being of substantially the same length, a closure member at each end of said tubular members having a flat face disposed against the ends of the several tubular members for closing off said annular spaces and having apertures therein communicating with the interiors of the tubular members of said second series where- 20 by the outer surfaces of said first series of tubular members and the inner surfaces of said second series of tubular members are utilized in radiating heat, passages for establishing communication between adjacent annular chambers, said 25 passages being disposed alternately at opposite ends of said tubular members, an inlet port for communicating with the annular chamber at one end of said series of tubular members and an outlet port communicating with the annular chamber at the opposite end of said series of tubular members, and tie rods extending between said end closure members and engaging therewith to retain said closure plates in a fluid-tight manner 30 against the ends of said tubular members in assembled relation.

3. A heat exchange unit comprising a series of tubular members arranged in parallel relationship, a second series of tubular members of smaller cross-sectional area than said first series, 45 one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several tubular members for closing off said annular spaces and having apertures 50 therein communicating with the interiors of the tubular members of said second series whereby the outer surfaces of said first series of tubular members and the inner surfaces of said second series of tubular members are utilized in radiating heat, 55 passages for establishing communication between adjacent annular chambers, said passages being disposed alternately at opposite ends of said tubular members, an inlet port for communicating with the annular chamber at one end of said series of tubular members and an outlet port communicating with the annular chamber at the opposite end of said series of tubular members, and tie rods extending between said end closure members and engaging therewith to retain 60 said closure plates in a fluid-tight manner against the ends of said tubular members in assembled relation, the intermediate portions of said tie rods being disposed within said annular fluid chambers.

4. A heat exchange unit comprising a series of

tubular members of elongated cross-section arranged in parallel relationship along an axis coincident with their shorter cross-sectional extent, a second series of tubular members of substantial similar cross-section as the tubular members of said first series but of smaller cross-sectional area than said first series, one each of said second series of tubular members being arranged centrally within each of said first series of tubular members to provide fluid chambers extending continuously about the smaller tubular members, said inner and outer tubular members being of substantially the same length, a closure member at each end of said tubular members having a flat face disposed against the ends of the several tubular members for closing off said fluid chambers and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, and an inlet port for communicating with the annular chamber at the opposite end of said series of tubular members.

5. A heat exchange unit comprising a series of tubular members of elongated cross-section arranged in parallel relationship along an axis coincident with their shorter cross-sectional extent, a second series of tubular members of substantially similar cross-section as the tubular members of said first series but of smaller cross-sectional area than said first series, one each of said second series of tubular members being arranged centrally within each of said first series of tubular members to provide fluid chambers extending continuously about the smaller tubular members, said inner and outer tubular members being of substantially the same length, a closure member at each end of said tubular members having a flat face disposed against the ends of the several tubular members for closing off said fluid chambers and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, an inlet port for communicating with the annular chamber at 60 one end of said series of tubular members and an outlet port communicating with the annular chamber at the opposite end of said series of tubular members, and tie rods disposed in said

fluid chambers and engaging at their opposite ends with the end closure members to retain said closure members in a fluid-tight manner against the ends of said tubular members in assembled relation.

6. A heat exchange unit comprising a series of tubular members arranged in spaced parallel relationship, a second series of tubular members of smaller cross-sectional area than said first series, one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several members for closing off said annular spaces and having apertures therein communicating with the interiors of the tubular members of said second series whereby the entire outer surfaces of said first series of tubular members and the inner surfaces of said second series of tubular members are utilized in radiating heat, passages for establishing communication between adjacent annular chambers, said passages being disposed alternately at opposite ends of said tubular members, and an inlet port for communicating with the annular chambers at one end of said series of tubular members, and an outlet port communicating with the annular chamber at the opposite end of said series of tubular members.

7. A heat exchange unit comprising a series of tubular members of elongated cross-section arranged in parallel relationship along an axis coincident with their shorter cross-sectional extent and with their elongated side wall portions in abutting relation, a second series of tubular members of smaller cross-sectional area than said first series, one each of said second series of tubular members being arranged centrally within each of said first series of tubular members to provide annular fluid chambers therebetween, said inner and outer tubular members being of substantially the same length, a closure member at each end of said tubular members having a flat face disposed against the ends of the several members for closing off said annular spaces and having apertures therein communicating with the interiors of the tubular members of said second series whereby the outer surfaces of said first series of tubular members and the inner surfaces of said second series of tubular members are utilized in radiating heat, passages for establishing communication between adjacent annular chambers, said passages being disposed alternately at opposite ends of said tubular members, and an inlet port for communicating with the annular chamber at one end of said series of tubular members and an outlet port communicating with the annular chamber at the opposite end of said series of tubular members.
